TAG-AFFIXING MACHINE.

1,296,749.

Specification of Letters Patent. Patented Mar. 11, 1919.

Application filed November 30, 1917. Serial No. 204,664.

To all whom it may concern:

Be it known that we, WILLIAM BORCHERT and FRED L. BORCHERT, citizens of the United States, residing at Rockford, in the county 5 of Winnebago and State of Illinois, have invented certain new and useful Improvements in Tag-Affixing Machines, of which the following is a specification.

This invention relates to the affixing of 10 tags to flat material and is of special utility in commercial laundries where small tags are affixed to customers' goods and subsequently marked with an identifying character. As will be seen later, however, our improvements are in no way limited to laundry 15 use, since we contemplate the affixing of tags to flat goods or material of any description; but since we have designed the present machine principally for use in laundries to affix 20 a tag of special construction, namely—a U-shaped metal, cloth covered tag to garments, we will, for purpose of clarity describe generally this adaptation to use.

Prior to the production of the present machine semi-automatic tag affixing machines offered to the laundrymen have been deficient in many respects so far as conditions and requirements of the laundry is concerned. A machine of this character must be universally used, hence it is desired that it shall be adapted equally well to large and small laundries. Simplicity and durability in construction and operation are therefore important factors and in these respects prior machines have not fulfilled the need. As a consequence much trouble is experienced in installing machines to operate properly, and in use the parts become clogged and worn and require repairs quite frequently so that in 40 these and other respects such machines have not satisfactorily met the desired needs.

In the present invention we have aimed primarily to overcome the deficiencies of prior machines and have devised a tag affixing machine altogether novel in both construction and manner of operation and which fully meets the conditions and requirements of large and small laundries and of other establishments where U-shaped tags or the like 50 are to be affixed to flat material.

We have also aimed to provide a machine of the character described which shall be

semi-automatic in operation, that is, shall require only simple manipulation to cause various operations resulting in the affixing of the tag, and which shall also be of such simple construction and of few parts that it may be produced at a comparatively low cost.

In furtherance of these general objects we have incorporated into our affixing machine many novel features of advantage and practicability. These might be mentioned briefly at this time as constituting various phases of our improvements and will be fully described and dealt with hereinafter. One of these objects is to provide a novel tag affixing device by means of which a tag may be very securely clamped or clenched to the edge of a flat piece of material by a simple downward pressing movement of the hands without removing them from the material after it has been positioned in the clenching mouth, or rather between the clenching jaws. This device embodies means by which the hand pressure applied in affixing the tag is multiplied in a very effective manner to secure the desired clenching pressure. Another object resides in the carrying of the tag affixing device from an "at-rest" or "work-receiving" position to a "tag-receiving" position at which a tag will be automatically fed into the mouth of the device from a magazine containing a large number of tags, whereupon the device will be returned loaded to its original position and may then be operated as first mentioned to affix the tag independently of the mechanism employed for performing the automatic tag-loading movement. A further object is to provide a novel tag-carrying means or magazine whereby the tags will be individually mounted and held in position and carried successively to the loading station at which they will be successively fed or loaded into the affixing device as mentioned. Our improvements also contemplate the provision of means for operating through the actuation of a single lever, the several mechanisms and devices just mentioned in timed relation and sequence in the feeding of tags to the affixing device and the moving of the latter to and from its work-receiving position. A still further object is to provide a machine of the character described which is portable and may be placed

on a bench, table, or any flat surface, and easily moved about if desired, and yet possess sufficient weight for all practical purposes.

5 These and other objects and attendant advantages will be better appreciated as the invention becomes more fully understood by reference to the following description when considered in connection with the accompanying drawings, in which—

10 Figure 1 is a side elevation of a tag affixing machine embodying our improvements, showing the affixing device in a work-receiving position;

15 Fig. 2 is a plan view of the machine, partially broken away to show the interior of the tag magazine;

20 Fig. 3 is a vertical sectional view taken substantially on the line 3—3 of Fig. 2;

25 Fig. 4 is a fragmentary view showing the affixing device moved to a clenching or clamping position;

30 Fig. 5 is a fragmentary view showing the parts having fed a tag into the affixing device;

35 Fig. 6 is also a fragmentary view showing the position of the operating lever when the parts have been moved to the position shown in Fig. 5;

40 Fig. 7 is a front elevation of the machine;

45 Fig. 8 is a cross-sectional view taken substantially on the line 8—8 of Fig. 3;

50 Figs. 9 and 10 are perspective views of the comb feeder and the tag feeder respectively; and

55 Fig. 11 is a perspective view of a laundry tag especially adapted to be handled by this machine.

Before entering into a detailed description of our improvements we believe a brief account of its functions will facilitate a clear understanding of the invention. It might first be mentioned that the tag especially adapted to be affixed is of the type generally known as a laundry tag of U-shape and, as shown in Fig. 11, consists of a U-shaped pliable metal body 14 enveloped by a fabric cover 15 so that when the tag is clenched onto a flat piece of material the spurs 16 secure the tag against displacement and the outer fabric affords surfaces adapted to receive the owner's identifying mark which may be applied either by a pen or a mechanical marking machine. In the present invention we mount the tags in rows on carriers or combs and place the same in a magazine. Mechanism is provided for feeding a comb in step by step movements to advance the tags successively to a feeding or loading station at which the tag thereat will be fed into the mouth of an affixing or clenching device. This device is movable from this tag-receiving position to a work receiving position at which the operator may

65 insert an edge of a garment or any flat piece of material into the mouth of the affixing device and consequently in the mouth of the tag therein and then press downwardly on said device without removing the hands from the garment and in this downward movement cause the tag to be flattened and firmly clenched onto the work. Upon release of the downward pressure the affixing device will automatically return to its original position and the tagged work may be withdrawn. The empty affixing device may then be moved to its tag-receiving position and loaded as previously mentioned. The operation of loading the affixing device is semi-automatic in that the operator must actuate 70 a handle which operates the mechanism for advancing the tag comb, moving the affixing device to and from the tag-receiving position and feeding a tag from the comb to the affixing device, these several operations taking place in proper sequence. Thus the operator simply moves the lever back and forth in a quick movement to place the machine in condition to affix a tag, and by a simple downward movement of the affixing device the tag is clenched. This operation may be repeated until the tags of a single 75 comb have been affixed whereupon a new comb of tags will be substituted for the empty one.

90 Coming now to the construction of the present embodiment of our improvements, we have provided a relatively flat base 17 equipped with a pair of spaced upright standards designated generally by characters 18 and 19, interposed between and upon which the several mechanisms mentioned are mounted. Of these, we will first consider the tag affixing or clenching device. It includes a pair of clenching or clamping 100 elements or jaws designated generally by the characters 21 and 22. The element 21 is shaped to provide spaced sides 23 joined by a cross head or jaw 24, the sides having respectively formed therein mouths 25 and 26 and laterally projecting ears or thumb rests 27. These mouths, it will be noted, are disposed at different elevations or planes, one above the other, for a purpose mentioned hereinafter. The element 21 constitutes 105 what might be termed a rigid jaw and the element 22 interposed between the sides 23 a movable jaw, since it is movable toward and from the jaw 24. The jaws are both supported and operated by simple compound 110 levers 28 and 29 disposed at both sides of the jaws and pivotally connected at one end 31 to the sides 23 of the jaw 21 and intermediate their ends at 32 to the jaw 22. The levers in turn are pivotally attached at 33 115 to the free end of arms 34 pivotally mounted at 35 upon the upstanding portions of the standards. It will be observed from the

foregoing that the jaws and the levers constituting the affixing device may be moved as an entirety about pivots 35 by rocking movement of the arms 34, thereby moving 5 said device bodily to and from a lowered or tag-receiving position in which the mouth of the clenching device is faced directly downward, and that when the arms 34 are locked against such movement by means described 10 hereinafter the affixing device may be moved downwardly about the pivots 33, or rather, the pivotal mounting of the levers, by pressure upon the thumb rests 27. During this downward movement of the affixing device 15 or clenching head, illustrated in Fig. 4, the jaw 22 will be moved toward the jaw 24 in a powerful clenching action, due to the mechanical advantage gained by the leverage arrangement shown. Thus the hand pressure 20 applied in pressing down on the thumb rests is multiplied and increasingly applied to the jaws in clenching a tag in the mouth of the head between the jaws, and consequently the tag will be very securely attached 25 to the work and also flattened to provide an effectual marking surface and to be as compact as possible. Means is provided for automatically returning the clenching head to its work-receiving position, consisting 30 in this instance of expansion springs 36 confined and concealed in the body of the jaws 22 and exerting their pressure against a pair of studs 37 depending from the jaw 24, as shown in Figs. 3 and 4. Obviously 35 the springs normally hold the jaws in the work-receiving position, shown in Fig. 3, and permit the jaws to be yieldingly moved to the clenched position shown in Fig. 4. The studs 37 also serve as stops which define 40 the back of the tag-receiving mouth and against which the arch or back of a tag is adapted to abut, as clearly shown in Fig. 4. In order to yieldingly hold a tag in the mouth and to prevent accidental displacement 45 of the tag therefrom we have provided a flat spring finger 38 adapted to yieldingly bear against the top of the tag. And because of the manner in which the spurs 16 are arranged at diagonally opposite corners 50 of the tag mouth as shown in Fig. 11, the mouths 25 and 26 of the clenching head are arranged in different planes in order that the work to be tagged may be easily and properly inserted into the tag mouth without interference with the spurs. It will be 55 observed that when a tag is positioned in the clenching head the mouths 25 and 26 are disposed adjacent to those inner corners of the tag which have no spurs, or, in other words, 60 the spurs are covered at the sides by the walls 23 due to the arrangement of the mouths 25 and 26. Consequently the edge of the work to be tagged will be inserted in an inclined manner one side higher than the

other as determined by the mouths 25 and 26 65 to avoid the spurs 16 and permit full insertion of the material into the tag mouth. From the foregoing it will be manifest that every precaution has been taken to produce an affixing device which any unskilled person 70 can easily and correctly operate and which is so designed that a very powerful clenching pressure is obtained with very few parts 75 of simple and inexpensive construction.

We will now consider the tag carriers and magazine and then follow with the tag feeding mechanism. The fore part of the base, somewhat enlarged and shaped to house the tag magazine, includes upright sides 39 which are surmounted by a cover plate 41. 80 The compartment 42 thus provided serves as a magazine in which is kept a plurality of tag carriers or combs each of which is adapted to carry a row of tags in substantially abutting relation so that a large number 85 of tags may be carried. A comb is formed of a body 43 preferably of sheet material and provided at one edge with equally spaced teeth 44 each of which is adapted to fit into the mouth of one tag centrally between the sides thereof, as shown clearly in Figs. 3 and 7. This form of tag carrier is 90 very desirable in that it may be easily loaded because the tags (which are sold separately) are contained in rows in boxes with the 95 mouths facing upwardly, allowing a comb to be inserted into the mouths of a whole row of tags simultaneously. Furthermore, a comb thus loaded with tags may be placed directly into the machine and serve as a carrier 100 which may be advanced in step by step movements by the feeder coöoperating with the comb teeth to thereby bring the tags successively to a loading station, and since the comb does not occupy the entire mouth of a 105 tag a feeding member may enter the mouth and feed the tag into the clenching device. A channel provided to receive the body 43 of a comb is arranged so that the tags travel in a plane in vertical alinement with the mouth 110 of the clenching head and in proximity to such mouth when it is in its lowermost or tag-receiving position. The channel may be formed in any suitable manner and in the present instance is made of sheet metal 115 plates 46 secured to the base. The inner walls 47 of the plates define the sides of the channel which receive the comb body 43 and the front ends of the outer walls are shaped to provide tapered guides 48 which cause 120 any uneven tags on the comb to be moved centrally thereof when a comb is manually slid into the channel 45 from the front of the machine. The remaining combs similarly loaded with tags may be stored in the 125 magazine at both sides of the central channel, and we have found that a simple and practical way of arranging the combs there-

in is to invert them so that the tags rest on the top of the base and the top edge of the combs are guided in slots 49 formed in a depending flange of the cover plate and serving to hold the combs in upright position. When a comb has been emptied, that is, fed completely through the machine, a loaded comb is withdrawn from the open front of the magazine, inverted to position the tags uppermost, and is then slid into the channel 45 until limited by a stop mentioned hereinafter, whereupon the tag supply is ready for use.

Means is now provided for removing one tag at a time from the comb and inserting it into the mouth of the clenching device and then to advance the comb one step to bring the next succeeding tag to the loading station. This includes a tag feeder and a comb feeder, designated generally by characters 51 and 52 respectively, and illustrated separately, in Figs. 9 and 10. Both are in reality simple rocking arms pivotally mounted at one end on a stationary shaft 53 in turn interposed between and mounted upon the standards. The tag feeder 51, it will be observed, is disposed in the path of travel of the central comb, and is partially parted longitudinally as at 54 to allow the comb to pass through the machine. The free end of the tag feeder normally rests on the base and is equipped with a pair of upstanding fingers 55 straddling the comb and headed as at 56. When a tag is positioned directly over the finger ends the feeder may be raised to carry its fingers into the tag mouth, remove the tag from the comb and insert the tag into the mouth of the clenching head which has been moved to the tag-receiving position by mechanism presently to be described. The headed fingers fit just snugly enough in the tag mouth to insure a proper hold of the tag and yet allow the fingers to be withdrawn from the tag after it has been fully moved into the clenching head mouth and engaged therein by the spring 38. The comb feeder 52 it will be seen, is equipped at its free end with a down-turned finger 57 overlying the comb and adapted to enter between two adjacent teeth thereof to move the comb lengthwise one step, that is, the distance between centers of two adjacent teeth. For this purpose the feeder 52, as noted in Fig. 9, is provided with a slot 58 through which the shaft 53 passes, permitting the desired lengthwise movement of the feeder. It will be apparent therefore that the comb feeder finger 57 is capable of a downward movement to engage in a comb and a lengthwise movement to advance the comb, and thence to be withdrawn from the comb and positioned again over the next succeeding tooth opening. Attention is here called to the fact that there

is no interference between the comb feeder 65 and the tag feeder because the latter is raised and lowered again while the former is withdrawn in its feed movement from the path of the tag feeder, as will be presently mentioned.

Mechanism for operating the tag and comb feeders and also for moving the clenching head to its several positions, is in the present instance, for purpose of simplicity, manually operable. It includes therefor, a hand crank or lever 59 fixed to the rock shaft 61 mounted on the standards forwardly of the shaft 53, as shown. The connection between the rock shaft and arms 34 for moving the clenching head is established through the agency of an arm 62 fixed to one of the pivot pins 35, an angular link 63 pivotally connected at 60 to the arm 62 and an arm 64 (Figs. 6, 7 and 8) loose on the rocking shaft 61 and pivotally connected by means of pins 65 to the lower end of the link 63. It will be noted that arm 64 is positioned on the rocking shaft adjacent to the outer side of the standard 19 and that the hand crank spaced outwardly from said arm is in reality a bell crank having an arm 66 through which motion is transmitted to the arm 64. A yielding and lost motion connection is provided between the arms 64 and 66 consisting of a spring 67 coiled about the shaft 61 and having one end engaging a lug 68 on a bell crank and the other end a lug 69 on the arm 64. The pressure of this spring is applied to constantly urge the head of the pin 65 against the wall of the recess 71 in an inner side of the arm 66, or in other words the spring serves to maintain a connection between the arms 64 and 66 holding them in fixed relation so that they will move together, but permits the arm 66 to be moved independently of the arm 64 in a counter-clockwise direction, viewing Fig. 6, against the pressure of the spring when the arm 64 is stopped from moving in such direction for a purpose to be presently mentioned. Concerning the connection between the rock shaft 61 and the arms 34 we have designed the same to automatically lock the parts connected with the shaft 61 against movement when the clenching head has been moved to its at-rest or work-receiving position. It will be observed, viewing Fig. 1, that the pivot 65 has been carried beyond a dead center line between the centers 60, 61 and 65 and is limited in such movement by abutment of the link 63 against the lug or stop 69. This locking effect may be broken, however, by moving the hand crank 59 in a counter-clockwise direction, and in continuing this movement of the crank to the position shown in Fig. 6 the clenching device will be moved from its work-receiving position to the tag-receiving position shown in

Fig. 5. This position of the clenching device is limited by abutment of its head against a fixed stop, such, for instance, as by the abutment of the ears 27 against the standards, or more particularly, the stops 72 fixed to the standards. In the interval of moving the clenching head to and from its work-receiving position the tag comb is advanced one step and a tag is fed into the mouth of the clenching device. The greater portion of the forward movement of the lever 59 is occupied by swinging the clenching device to the tag-receiving position and the latter portion of such movement is employed to operate the comb feeder and the tag feeder. In the forward movement of the hand crank 59, motion is transmitted from its arm 66 to the arm 64 and consequently to the clenching device, until the latter is stopped by the abutment 72, whereupon the crank may be moved during the final portion of its stroke independently of the clenching device and its operating connections, a short distance as shown in Fig. 6. During this final movement the shaft 61 will be rocked to operate the feeder 51. It will be manifest that this final movement is possible due to the yielding connection between the hand crank and arm 64 and is against the pressure of the spring 67. Upon releasing the lever the spring will return the lever until the wall of the recess 71 abuts against the stud 65, whereupon a positive connection is established so that all parts connected to the rock shaft 61 are moved together and returned to their normal position, shown in Figs. 1 and 3. When the clenching device has been thus returned to normal position a pair of thrust arms 73 secured to the rock shaft 61 just within the inner sides of the standards will be brought into abutting relation with the free ends of the arms 34, shown clearly in Fig. 3, and thereby serve as an effectual means for locking the arms 34 against movement in one direction, while movement in the opposite direction is precluded by reason of the locking effect of the link 63. The means operable between the rock shaft 61 and the comb and tag feeders consists of an arm 74 secured to the rock shaft and adapted to operate at this free end with cam surfaces on the comb and tag feeders. As shown in Fig. 3 the arm 74 engages the inclined surface 75 of the comb feeder 52. This comb feeder it will be noted, is sustained in the position shown by means of an overhead extension 76 which rests on the cam surface 77 formed integral with the collar of the arm 74. As this arm 74 is oscillated in a counter-clockwise direction, viewing Fig. 3, by movement of the hand crank forwardly, the first action to occur will be a lowering of the comb feeder finger 57 into engagement

with the comb, due to the fact that the cam 77 is revolved sufficiently to allow the part 76 of the comb feeder to be lowered under the influence of a suitable spring 78. When the comb feeder has been thus lowered the arm 74 will engage the abrupt inclined surface 79 of the cam feeder and will move the latter lengthwise a sufficient distance to advance the comb one step as mentioned above and to thereby position the tag "A" directly over the feeder head 56 at a loading or feeding station. Continuing the movement of the arm 74 in a counter-clockwise direction by the final forward movement of the hand lever mentioned above with reference to Fig. 6, the end of arm lever will engage the surface 81 of the tag feeder and will cause the latter to be lifted, that is—swung upwardly at its free end so as to enter a tag and feed it into the mouth of the clenching device, as indicated in Fig. 5. During this final movement it will be observed that the free end of the comb feeder which overlies the tag feeder will be bodily lifted upwardly without performing any function, and will be lowered again into engagement with the comb when the tag feeder 51 is lowered by reason of the reverse movement of the hand crank 59 and the arm 74. The latter arm it will be observed, operates in its reverse movement directly on the surface 82 of the tag feeder and moves the same to its lowered normal position. During the latter part of the movement of the arm 74, when the hand crank 59 is being moved rearwardly, the cam 77 will raise the comb feeder to withdraw its finger 57 from the comb and the free end of the arm 74 will engage the inclined surface 75 and move the comb feeder forwardly to the position shown in Fig. 3. From the foregoing it will be manifest that aside from the direct affixing of a tag the movement of the various parts are all performed and controlled by simply moving the hand crank forwardly as far as it will go and then returning the crank to its original position. In thus moving the crank it has been seen that the first action to occur is the withdrawing of the thrust arm 73 from the arms 34 and the breaking of the lock 63 which allows the arms 34 and consequently the clenching device to be swung to tag-receiving position. As the hand crank 59 is swung forwardly the clenching device is moved to the lowered or tag-receiving position and brought to a stop, and about the same time the comb feeder advances the comb one step through the agency of the cam 79 and arm 74. Then during the final short movement of the hand crank after the clenching device has been brought to rest a tag is fed into the mouth of said device by the tag feeder 51. These

operations take place very rapidly and in proper timed sequence, since it will be obvious that in operation the operator desires to load the machine as quickly as possible and consequently draws the hand crank forwardly in a rapid stroke. Similarly the several parts are rapidly returned to their original position and are properly locked therein by a quick return movement of the hand crank. The clenching device is now ready for use and may be operated as described above to affix or clench a tag to the edge of a piece of material. It will be observed that the clenching device when in this position may operate entirely independently of the other operating mechanism and that the means for supporting the clenching device, namely—the arms 34, are rigidly maintained and held against the thrust arms 73 which withstand the backward and downward thrust upon the arms 34 following from the downward thrust upon the clenching device. Manifestly, after the tag has been affixed and the affixing device returned to its "at-rest" position the tagged material is free to be removed from the mouth of said device. Referring now to the placing of a comb into the machine, the hand crank 59 is moved forward to a position in which the comb-feeder is lowered and moved back so that its finger 57 is positioned at its rear-most point of travel and in the path of the comb so as to serve as a stop for limiting the advance of the comb into the channel. Thus when the hand crank is further moved forward the first tag will be fed into the affixing device and upon the next operation of the hand crank the finger 57 will enter the first empty tooth space and advance the comb one step.

It is believed that the foregoing conveys a clear understanding of the manner in which the objects prefaced above have been accomplished, and we wish it to be understood that the particular embodiment of our improvements shown is simply for the purpose of illustrating the principles thereof. Hence various changes might be made in the construction and arrangement of parts without departing from the spirit and scope of the invention as expressed in the appended claims, in which—

We claim:

1. A device for clamping tags or the like onto flat material comprising a pair of relatively movable jaws, and means for supporting the jaws consisting of a lever pivotally mounted at one end and connected at its free end respectively to each jaw, the pivots of which are unequally distant from the pivot axis of the lever, so that when the lever is swung about its pivotal mounting the jaws will be relatively moved by the lever in a clamping action.

2. In a tag-affixing machine, a pair of relatively movable jaws between which a tag may be placed to be clenched by closing movement of the jaws, and a lever pivotally mounted at one end and pivotally connected at its free end to each of the jaws, the jaw pivots being unequally distant from the pivot axis of the lever, whereby when the lever is swung about said axis the jaws will be relatively moved by the lever in a closing action.

3. In a machine of the character described, a tag affixing device comprising spaced sides fixed to a cross portion which constitutes a jaw, a second jaw interposed between said sides and movable toward and from the first jaw, supporting means, a pair of levers pivotally mounted on said supporting means and pivotally connected to said jaws, whereby when the affixing device is carried by the levers about the pivotal mounting thereof on the supporting means the jaws will be relatively moved in a clamping action.

4. In a tag affixing machine, a tag affixing device comprising a casing having spaced sides and a cross portion constituting a jaw, a second jaw interposed between said sides and movable toward and from the first jaw, each side of the casing being shaped to provide an opening or mouth to the jaws, said mouths being disposed at different distances from or with respect to the first jaw, and means for causing the jaws to be relatively moved in a clamping action.

5. A tag affixing means comprising relatively movable jaws normally held open for the reception of a tag and a piece of material to be tagged by closing movement of the jaws, and supporting means for the jaws consisting of a pair of levers pivotally mounted at one end and connected at their free ends with said jaws at unequal distances from the pivots of the levers, whereby upon swinging the levers they will move the jaws relatively in a clamping action.

6. A tag affixing means comprising relatively movable jaws, supporting means therefore consisting of a pair of levers each pivotally mounted at one end and connected at its free end to each of said jaws at unequal distances from the pivot axis of the lever, whereby upon swinging the levers they will move the jaws relatively in a clamping action, and means constantly urging the levers in a direction to hold the jaws in an open or work-receiving position.

7. In a tag affixing machine, a tag affixing device having relatively movable parts for clenching tags onto flat material, a pivotally mounted lever structure pivotally connected respectively to each of said relatively movable parts at unequal distances from its pivotal mounting so that when swung on such mounting said parts will be relatively moved

thereby in a clamping action, and means allowing said lever structure to be moved independently of its clamping action movement to carry the affixing device into and out 5 of a tag-receiving position.

8. In a tag affixing machine, a tag affixing device having relatively movable parts for clenching tags onto flat material, a pivotally mounted lever structure pivotally connected 10 respectively to each of said relatively movable parts at unequal distances from its pivotal mounting so that when swung on such mounting said parts will be relatively moved by said lever structure in a clamping action, 15 means allowing said lever structure to be moved independently of its clamping action movement to carry the affixing device into and out of a tag-receiving position, means for feeding a tag into the affixing device 20 when in said tag-receiving position, and a common operating means for causing the affixing device to be moved to and from said tag-receiving position and for causing the tag feeding means to feed a tag into the affixing device 25 when the latter has been moved to said tag-receiving position.

9. In a tag affixing machine, a tag affixing device having relatively movable parts for clenching tags onto flat material, a pivotally mounted lever structure pivotally connected 30 respectively to each of said relatively movable parts at unequal distances from its pivotal mounting so that when swung on such mounting said parts will be relatively moved thereby in a clamping action, means allowing the lever structure to be moved independently of its clamping action movement to carry the affixing device into and out of a tag-receiving position, means for feeding a tag into the affixing device when in said tag-receiving position, and mechanism including 35 a member movable back and forth for moving the affixing device to said tag-receiving position and to feed a tag to said device 40 when the member is moved in one direction and for returning the affixing device to normal position upon movement of said member in an opposite direction.

10. In a tag affixing machine, the combination of a tag magazine, an affixing device, means for moving the affixing device into and out of proximity to the magazine, means for feeding a tag from the magazine into the affixing device when the latter has 50 been positioned in proximity to the magazine, a rock-shaft, means for rocking the same in opposite directions, and connections between the rock-shaft, the affixing device and the feeding means for moving the affixing device into tag-receiving position and for causing the tag feeding means to feed a tag into the affixing device when the rock-shaft has been moved in one direction and for returning the affixing device and tag- 55

feeding means to normal position when the 65 rock-shaft has been moved in the opposite direction.

11. In a tag affixing machine, the combination of a clenching device having relatively movable jaws between and by which 70 a tag may be clenched onto a piece of material inserted between the jaws, the clenching device being movable as an entirety to and from a tag-receiving position, a tag magazine, means for feeding a tag from 75 the magazine into the clenching device between the jaws thereof when said device has been moved to said tag-receiving position, and mechanism operated by a single operating member for causing the clenching 80 device to be moved to said tag-receiving position and for operating said tag feeding means.

12. In a tag affixing machine, the combination of a clenching device movable to 85 and from a tag-receiving position, means for carrying a row of tags, means for moving the tag-carrying means in step by step movements to successively position the tags at a feeder station, and means for removing 90 a tag at the feeding station from said carrying means and for feeding the tag into the clenching device when the latter has been moved to its tag-receiving position.

13. In a tag affixing machine, the combination of means for affixing a tag, a comb adapted to carry a row of tags, means for moving the comb in step by step movements to successively position the tags at a feeding station, and means for removing a tag 100 at said station from the comb and positioning the tag in said affixing means.

14. In a tag affixing machine, the combination of means for affixing a tag, means for carrying a row of tags, means for moving the tag-carrying means in step by step movements to successively position by each such movement a single tag at a feeding station, and means for removing the tag at the feeding station from said carrying 105 means and for placing the tag in coöperative relation with the affixing means.

15. In a tag affixing machine, the combination of means for affixing a tag, a carrier constructed to carry a row of tags and 110 movable in step by step movements to successively position by each such movement a single tag at a feeding station, and means for moving the tag at the feeding station into coöperative relation with the tag affixing means.

16. In a tag affixing machine, the combination of means for affixing a tag, a carrier constructed to carry a row of tags and 115 movable in step by step movements to successively position by each such movement a single tag at a feeding station, means for moving the tag at the feeding station into

coöperative relation with the tag affixing means, and means operated by a single member to cause said carrier and tag moving means to be operated in timed relation whereby the tag carrier will be advanced to position a tag at the feeding station and the tag moving means will move this tag into coöperative relation with the affixing means.

10 17. In a tag affixing machine, the combination of a device for affixing a tag and movable to and from a tag-receiving position, a carrier constructed to carry a row of tags and being movable in step by step movements to successively position the tags at a feeding station, and means for removing the tag at the feeding station from the carrier and positioning the tag fully into the affixing device when the latter has been moved to its tag-receiving position.

15 18. In a tag affixing machine, the combination of a device for affixing a tag and movable to and from a tag-receiving position, a carrier constructed to carry a row of tags and being movable in step by step movements to successively position the tags at a feeding station, means for removing the tag at the feeding station from the carrier and feeding the tag fully into the affixing device when the latter has been moved to its tag-receiving position, and mechanism for operating the tag affixing device, tag carrier and tag feeding means in timed relation, whereby to move said affixing device and tag carrier respectively to tag-receiving and tag-feeding positions and to then operate the tag feeding means.

20 19. In a tag affixing machine, the combination of a device having parts relatively movable in a clamping action for affixing a tag to a piece of material inserted between said parts, said device being movable as an entirety to and from a tag-receiving position, means for causing a row of tags to be moved in step by step movements to successively position the tags at a feeding station, and means for moving the tag at the feeding station into the affixing device when the latter has been moved to its tag-receiving position.

25 20. In a tag affixing machine, the combination of a device for affixing U-shaped tags and movable to and from a tag-receiving position, a comb provided with teeth each of which is adapted to carry one of said tags, means for moving the comb in step by step movements to successively position the tags at a feeding station, means for removing the tag at the feeding station from the comb and placing the tag into the affixing device when the latter has been moved to its tag-receiving position.

60 21. In a tag affixing machine, the combination of means for affixing a U-shaped tag

to flat material, a carrier provided with a row of teeth each of which is adapted to enter the mouth of one of said tags, means for moving said carrier to successively position its tags at a feeding station, and means for causing the tag at the feeding station to be fed to the affixing means.

65 22. In a tag affixing machine, the combination of means for affixing U-shaped tags to flat material, a carrier provided with a row of teeth each of which is adapted to enter the mouth of a tag, means for removing one tag at a time from the toothed carrier, and means for positioning the removed tag in the affixing means.

70 23. In a tag affixing machine, the combination of a tag carrier having a series of teeth each of which is adapted to enter the mouth of a tag and to thereby support the same, and means engageable with the teeth of the carrier for moving the same in step by step movements for successively positioning the tags at a feeding station.

75 24. In a machine for affixing U-shaped tags to flat material, the combination of a carrier having a series of teeth each of which is adapted to enter the mouth of a tag and to thereby support the same, means for removing one tag at a time from the carrier, and means engageable with an empty tooth of the carrier for moving the same a given distance to position the next succeeding tag-equipped tooth in operative relation to said tag removing means.

80 25. In a tag affixing machine, the combination with means for affixing U-shaped tags to flat material, of a carrier equipped with a row of teeth adapted for carrying a row of tags, and mechanism for removing a tag from one of the teeth and then engaging an empty tooth to advance the carrier to a position in which the next succeeding tag may be removed.

85 26. In a tag affixing machine, the combination of a tag affixing device movable from a work-receiving to a tag-receiving position, a carrier adapted to carry a row of tags and being movable in step by step movements to successively position its tags at a feeding station, a feeder for moving the tag at the feeding station into the affixing device when the latter has been moved to its tag-receiving position, means for advancing the tag carrier in said step-by-step movements, and mechanism for operating the foregoing devices in timed relation for causing a tag to be moved to the feeding station and thence into the affixing device.

90 27. In a tag affixing machine, the combination of a tag affixing device movable from a work-receiving to a tag-receiving position, a carrier adapted to carry a row of tags and being movable in step by step movements to carry the tags to a feeding station, a feeder

for moving the tag at the feeding station into the affixing device when the latter has been moved to its tag-receiving position, means for advancing the tag carrier in said 5 step by step movements, and mechanism including a single operating member movable in one direction for causing the carrier to position a tag at the feeding station, for moving the affixing device to its tag-receiving 10 position and for causing a tag to be fed into the affixing device.

28. In a tag affixing machine, the combination of a tag affixing device movable from a work-receiving to a tag-receiving position, 15 a carrier adapted to carry a row of tags and being movable in step by step movements to successively position its tags at a feeding station, a feeder for moving the tag at the feeding station into the affixing device when 20 the latter has been moved to its tag-receiving position, means for advancing the tag carrier in said step by step movements, and mechanism for operating the foregoing in timed relation, including a single operating 25 member having one movement in which to cause the affixing device to be moved to tag-receiving position and to cause a tag to be fed into the clamping device and having another movement in which to return the 30 affixing device and other parts to their normal position.

29. The combination of means for affixing U-shaped tags to flat material, a carrier provided with a plurality of teeth each of which 35 is adapted to engage within the mouth of a tag and thereby support the same, and a means for removing one tag at a time from the carrier so that the removed tag may be affixed by said affixing means.

40 30. In a tag affixing machine, a comb having a series of teeth adapted for supporting a row of tags, and means for moving the comb in step by step movements to successively position the tags at a loading station.

45 31. In a tag affixing machine, a comb having a series of teeth each of which is adapted to enter the mouth of a tag and to thereby support the same, and tag feeding means adapted also to enter the mouth of a tag 50 positioned on one of the comb teeth and to remove the tag therefrom.

32. The combination of means for affixing U-shaped tags to flat material, a comb each tooth of which is adapted to enter the mouth 55 of the tag to support the same and allow a portion of the tag to project beyond both sides of the tooth, and a feeder having spaced fingers adapted to straddle the comb and enter the mouth of a tag at both sides 60 of the comb and to remove the tag therefrom.

33. In a tag affixing machine, a tag affixing device movable back and forth from a work-receiving to a tag-receiving position,

means for carrying a row of tags and movable to successively position each tag at a feeding station, a pair of rocking arms one of which is adapted to remove the tag at the feeding station and to place it into the affixing device when the latter is in tag-receiving 70 position, and the other arm of which is adapted to advance the tag-carrying means in step by step movements to successively position the tags at the feeding station, and means for moving the affixing device to and 75 from its tag receiving position and for operating said rocking arms in predetermined timed relation.

34. In a tag affixing machine, a tag affixing device movable back and forth from a work-receiving to a tag-receiving position, 80 means for carrying a row of tags and movable to successively position each tag at a feeding station, separate means for advancing the tag carrier in step by step movements for successively moving the tags to the feeding station and for feeding the tag thereat into the affixing device when the latter is at its tag-receiving position, and mechanism to operate in predetermined 85 timed relation said affixing device and said separate means to move the affixing device to and from its work-receiving position and during the interval of such movement to feed a tag from the carrier into the affixing 90 device.

35. In a tag-affixing machine, the combination of a tag-affixing device having relatively movable jaws for clamping a tag onto a piece of material inserted between the 100 jaws, a tag magazine, means for moving the affixing device as an entirety from a work-receiving position to a tag-receiving position, and means for feeding a tag into the affixing device between the jaws thereof at 105 the tag-receiving position.

36. In a tag-affixing machine, the combination of a tag-carrier having a serrated face for carrying a row of tags, and means operable upon said serrated face for advancing the carrier and its tags. 110

37. In a tag-affixing machine, a tag-affixing device having normally separated jaws between which a tag may be positioned and which are relatively movable in a clamping action to affix the tag therebetween to a piece of material inserted between the jaws in co-operative relation with the tag, a swinging support for said tag-affixing device upon which the latter is movable as an entirety 120 into and out of work-receiving position, and means for feeding a tag into the affixing device during the interval of its movement into and out of said work-receiving position.

38. In a tag-affixing machine, the combination of a pair of relatively movable jaws, levers each pivotally connected at one end at spaced points to each of the jaws and

pivotedly mounted at their opposite ends on fixed pivots, by reason of which construction the levers when swung about their pivots will close the jaws in a clamping action to thereby affix a tag.

39. In a tag-affixing machine, the combination of a tag-affixing device having normally separated jaws which are relatively movable in a clamping action to affix a tag to a piece of material inserted between the jaws, a tag magazine, a rock shaft, means for

rocking the shaft, and means operated by the shaft during movement thereof in one direction for moving the tag-affixing device to a tag-receiving position and feeding a tag from the magazine to said device, and for returning the tag-affixing device to normal position during movement of the shaft in the opposite direction. 15
